CONTROL MECHANISM FOR HYDRAULIC SYSTEMS OF ROTARY DRILLING RIGS

Robert R. Crookston, Houston, Tex., assignor, by
mesne assignments, to Standard Oil Development Company, Elizabeth, N. J., a corporation of Delaware

Application November 29, 1950, Serial No. 198,189

3 Claims. (Cl. 254—173)

This application is directed to a control mechanism for a hydraulically controlled system for drilling oil wells of the type disclosed in U. S. Patents 1,831,437, Brantly, November 10, 1931; 2,133,016, Brantly, October 11, 1938; and 2,489,449, Crookston, November 29, 1949.

More specifically, the device of the present invention is a control mechanism to be used on a rotary drilling rig which is provided with a hydraulic system controlling the rate of feed-off and having a weight indicator for the drill bit which is capable of producing an electrical signal. The control mechanism of the present invention is arranged to be activated by electrical signals from the weight indicator and when so activated alters the rate of flow through the hydraulic system in response to said electrical signals. Other objects and advantages of the present invention will be seen from the following description taken in conjunction with the drawing in which:

Fig. 1 is in the form of a diagrammatic flow sheet showing a preferred embodiment of the system of the present invention;

Fig. 2 is an elevation, partly in section, showing details of construction of a suitable compressed air valve shown schematically in Fig. 1;

Fig. 3 is a view taken along line III—III of Fig. 2; and

Fig. 4 is a schematic showing of the relationship between parts of a rotary drilling rig and a weight indicator assembly, parts of which are shown in Fig. 1.

Turning now specifically to the drawing and first to Fig. 1, a suitable unit for producing electrical signals in response to changes in the weight carried by the drill bit is designated by the part enclosed within dashed lines and identified by I. The valve mechanism activated in response to the signals produced by group I is enclosed with a dashed line and designated as II. Details of construction of assembly II are shown in Figs. 2 and 3. The signal of the system is arranged to control the rate of flow of hydraulic fluid through a series of connected lines provided with suitable valves which is designated as III. It will be understood that the structure identified by III may be part of a complete hydraulic system such as described in U. S. Patents 1,831,437, 2,133,016, and 2,489,449.

In Fig. 1 the receiving unit C of the weight indicator assembly IV is shown. The weight indicator assembly IV is shown schematically in Fig. 4 in relationship to the parts of the conventional hoisting apparatus for rotary drilling rig.

In Fig. 4 drawworks N is provided with drilling line 2. By means of a derrick and crown block (which have been omitted from the drawing in order to simplify it) the drilling line 2 suspends the travelling block 3, swivel 4 and kelly 5 which passes through rotary 6, the lower end of the kelly being attached to the drilling pipe which is not shown since it is in the bore-hole. The weight indicator assembly IV consists of weight responsive element 7 arranged in the swivel and connected through electrical lead 8 to receiving unit C.

Turning now specifically to Fig. 1 and to that portion of the assembly designated by I, a split potentiometer A consists of resistances 11, 12, and 13 connected in series and having a slide or contact member 14. The resistances are connected through leads 15 and 16 to the secondary 17 of a center tap transformer B. Contact member 14 is secured to or mounted on a rotatable shaft 18 which is the shaft of receiving unit C of weight indicator assembly IV and moves angularly in response to variations in the weight carried by the drill bit. Since such weight indicators are known to the art, the details of construction are not shown. The primary 19 of transformer B is connected through leads 20 and 21 to a suitable source of alternating current 22.

Changes in the output of potentiometer A are transmitted to two-phase positioning motor D of II. One of the field coils 23 of motor D is connected through lead 24 to the center tap 25 of a secondary 17 of transformer B and through lead 16 to contact 14 of potentiometer A. The other field coil 26 of motor D is connected through conductors 27 and 21 to alternating current supply 22 and through conductor 28 to one plate of condenser 29. The other plate of condenser 29 is connected through make and break switch 30 and conductors 31 and 20 to alternating current supply 22. A two-phase motor E is coupled through shaft 32 to interrupter cam 33 arranged to activate make and break switch 30. Two-phase motor E is connected to the source of alternating current 22 by conductors 34 and 29 and 35 and 21.

The purpose of the arrangement of two-phase motors D and E in conjunction with the weight indicator C is to insure that the bias exerted by motor D is instantly responsive to changes in the position of potentiometer slide 14. By the use of interrupter switch 30 which is continuously interrupted by interrupter cam 33, the effect of hysteresis in two-phase motor D is largely overcome.

Valve mechanism F also forms a part of II. Valve mechanism F consists of a valve casing 40 having a central passage 41 of cylindrical shape with piston 42 slidably arranged therein. Portion 40 has inlet ports 43, 44, 45 and 46 and is closed with an end plate 47 which has an outlet 48. Piston 42 which is arranged for longitudinal movement along the cylindrical wall 41 of the wall body is of generally cylindrical shape provided with circumferentially extending groove 49 at its center portion which is connected through radially extending port 50 and longitudinally extending port 51 with the end 52 of the piston. The other end 53 of the piston is connected through rod 54 and mechanical linkage G to two-phase motor D.

Two-phase motor D drives shaft 60. Mounted on shaft 60 are gears 61 and 62. Gear 62 is arranged to mesh with toothed quadrant 63 which is mounted on shaft 64 and has secured thereto a downwardly extending lever arm 65 which is connected through pivoted arm 66 to piston rod 54. Shaft 60 is biased to a predetermined normal position by means of a rack 67 which meshes with the teeth of gear 61. The ends of rack 67 terminate in heads 68 with springs 69 arranged around each end of rack 67 and each spring 69 having an end in contact with the frame 70 of assembly G and its other end in contact with a head 68.

Thus when two-phase motor D rotates shaft 60 and forces rack 67 from its normal position a bias is exerted on the rack to return it to the normal position. The continual interruption of the current to motor D caused by the activation of switch 39 substantially eliminates the effect of hysteresis in the two-phase motor D and allows a substantially instant response in changes in the current resulting from changes in the position of potentiometer A. Rotation of motor D causes movement of piston 42 in cylinder 40 through the linkage described.

The hydraulic assembly III consists of one-way valves 70, 71, 72, and 73, valves 74 and 75 which are controlled by air pressure and a needle valve 76 which is also controlled by air pressure. Branched line 77 connects to the inlet of one-way valve 70 and to the outlet of one-way valve 72. Branched line 78 connects to the inlet of one-way valve 71 and to the outlet of one-way valve 72. Line 79 connects the two outlets of one-way valves 70 and 71. Line 80 connects the inlets of valves 72 and 73. Line 81 with valves 74 and 76 arranged therein connects lines 79 and 80. Line 82 with valve 75 arranged therein connects lines 79 and 80.

Pump M is mechanically connected to draw-works N. Hydraulically, one side of the pump is connected to line 77 and the other side to line 78. It will be understood that one of the lines is connected to the inlet of pump M and the other line to the outlet of pump M but in the manifold shown it is immaterial which side is the inlet and which side is the outlet and for that reason they are not specifically designated. Pump M is shown schematically in the drawing since specific details of construction of suitable pumps are shown in my Patent 2,489,449 and in the Brantly Patents 1,831,437 and 2,133,016, heretofore mentioned.

The activating mechanism of valve 74 is connected by compressed air line 83 to port 43 of valve F and the activating mechanism of valve 75 is connected by compressed air line 84 to port 46 of valve F. Air is supplied to line 83 from a

suitable source of compressed air, not shown, connected by inlet line 85 containing orifice 86. To allow an adjustment of the speed of operation of valve 74, an adjustable volume 87 is connected to line 83 through branch 88.

Line 84 is connected to a suitable source of air supply, not shown, through line 89 containing orifice 90. In order to allow adjustment in the speed of operation of valve 75 adjustable volume 91 is connected to line 84 through branch 92.

Needle valve 76 in the hydraulic system III is provided with a rotatable stem 93 on which is mounted a toothed wheel 94 which is rotated by a mechanism which is in effect a pair of air motors with their operation controlled by valve F. A cylinder and piston assembly H is arranged to rotate toothed wheel 94 in a clockwise direction and a cylinder and piston assembly J is arranged to rotate toothed wheel 94 in a counter-clockwise direction. Each of the assemblies H and J consists of a cylinder 100, a piston 101, piston rod 102 connected to the piston, a ratchet member 103 pivoted to the end of the piston rod and arranged in engagement with toothed wheel 94 and a spring 104 is arranged to bias the piston 101 toward the head end of cylinder 100. Piston and cylinder assembly H is connected by line 105 to a compressed air assembly K and assembly J is connected through line 106 to assembly L. Assemblies K and L are identical to each other. Each has a line 107 which contains an orifice 108 and is connected to an air supply line 109 and to the inlet of interrupter valve 110. The outlet of the interrupted valve of assembly K is connected through line 111 to port 44 of valve F and the outlet of the interrupted valve of assembly L is connected through line 112 to port 45 of valve F. Connected to line 107 of each assembly K and L is a manifold consisting of line 113 containing one-way valve 114 and orifices 115 and line 116 containing orifice 117. Orifices 115 and 117 are connected through branched line 118 to the activating mechanism of interrupter valve 110 and to variable volume 119.

The operation of assemblies K and H is in effect an air motor which operates only when its exhaust is allowed to discharge to the atmosphere. When the device is allowed to discharge to the atmosphere the cycle is as follows: Air from air supply line 109 passes through orifice 108 into cylinder 100 of assembly H and through orifice 117 into volume 119 and to the activating portion of interrupter valve 110. The pressure eventually builds up to a value in the operating portion of interrupter 110 sufficient to cause this valve to open whereupon air discharges through line 111, air being withdrawn from cylinder 100 as well as from volume 119. The one-way valve 114 insures that the air is quickly discharged from the operating portion of valve 110 as well as from cylinder 100. The discharge of the air in this manner causes piston 101 to move upwardly and to turn the toothed wheel 94 through an arc in the clockwise direction. After a fixed interval of time interrupter valve 110 closes allowing the air from air supply line 109 and bleeding through orifice 108 to fill cylinder 100, thus forcing piston 101 downwardly and gradually filling the operating portion of valve 110 until the predetermined pressure for activating valve 110 is again reached, whereupon the valve discharges and the cycle is repeated.

The combination of assemblies J and L operates in exactly the same manner as the assem-

semblies H and K, except assembly J rotates toothed wheel 94 in the counterclockwise direction.

The exhaust from assemblies H and K through line 111 is controlled by the position of valve F. In like manner, the exhaust from assemblies J and L through line 112 is controlled by valve F.

Valve 74 is activated by exhausting it at a faster rate than air can pass from the air supply means through orifice 86. This is controlled by valve F. Similarly, valve 75 is activated by exhausting through line 84 at a faster rate than air can pass from the air supply means through orifice 90. This is also controlled by valve F.

In drilling with a rotary drilling rig, as is well known to the art, part of the total weight of the drill stem is carried by the drilling line so that only a portion of the total weight of the drill stem rests on the drill bit. In the following description where the weight carried on the drill bit is mentioned, it will be understood that a decrease on the weight carried on the drill bit is necessarily accompanied by an increase in the weight supported by the drilling line and vice versa.

In the use of the apparatus described, the weight indicator C is adjusted so that when a predetermined range of weight is carried by the drilling bit, slide 14 has a normal position between resistances 11 and 13 so that it makes no contact with either of these resistances as long as the weight on the bit stays within said predetermined range. In this selected range the valve member 42 of valve F is in its normal position with groove 49 between ports 44 and 45. If the weight carried by the drill bit decreases, the slide 14 of potentiometer A moves from its normal position to activate motor D in an amount sufficient to bring ring 49 of valve member 42 adjacent port 45. (The electrical connection of the potentiometer A with two-phase motor D to accomplish this result will be apparent to a workman skilled in the art.) In this position air exhausts from the assemblies L and J to cause toothed wheel 94 to be moved counterclockwise, thus opening needle valve 76 to cause an increased flow of fluid through assembly III which allows a faster feed-off and should tend to increase the weight on the bit to bring it back to normal. If the correction brought about by exhausting air from port 45 through valve F is not sufficient the weight on the bit will continue to decrease until it reaches such a value that the weight indicator with electrical connections including motor D will change the setting of valve F to bring ring 49 of valve member 42 adjacent port 46; when this occurs air exhausts through line 84 and causes valve 75 (which for convenience in describing the results of its activation is called quick application valve) to open, allowing hydraulic fluid to flow through line 82. Valve 75 will remain at this setting until the weight on the bit increases to such an amount that the controls move valve member 42 to the left, taking ring 49 out of contact with port 46 whereupon quick application valve 75 closes.

In the operation of the device described, if the weight on the bit increases beyond the predetermined normal range, the movement of slide 14 of potentiometer A in conjunction with two-phase motor D will cause valve member 42 to move to the left to bring ring 49 adjacent port 44. When this occurs air can bleed out from assemblies H and K through lines 105 and 111 which, in turn, will cause assembly H to move

toothed wheel 94 in the clockwise direction closing needle valve 76 which will reduce the amount of liquid flowing through the hydraulic system. As long as the weight on the bit is such that line 111 exhausts through valve F, assembly H moves toothed wheel 94 arcuately at intervals progressively closing needle valve 76. However, if the weight on the bit increases still more, the potentiometer assembly A and two-phase motor D will force valve member 42 still further to the left so that ring 49 is adjacent to port 43; when this occurs valve 74 (which for convenience in describing the results of its activation on the drilling system is called the drill-off valve) is exhausted through line 83 closing this valve and which, in turn, stops fluid circulation through assembly III (since valve 75 is normally closed) and drill-off valve 74 will remain closed as long as the weight on the bit is excessive which, in turn, will cause member 42 to remain in its central left-hand position. When the weight on the bit is decreased to a predetermined value, the member 42 will be moved to the right so that line 83 can no longer exhaust through port 43, thus opening valve 74 and allowing fluid to pass once more through the hydraulic system and be controlled by the needle valve 76.

While I have disclosed this specific embodiment of the present invention, it will be obvious to a workman skilled in the art that various changes in the sizes, shapes and arrangements of the parts may be made without departing from the scope of the present invention.

Having fully described and illustrated a preferred embodiment of the present invention, what I desire to claim is:

1. A control system for controlling the speed of rotation of the drawworks of a rotary drilling rig having a weight indicator capable of producing signals varying in response to changes in the weight carried by the drill bit and having a hydraulic system for altering the weight carried by the drill bit comprising, in combination, a pump mechanically connected to the drawworks for pumping hydraulic fluid upon rotation of the drawworks, a hydraulic circuit connecting an outlet of said pump with an inlet thereof, said hydraulic circuit having a manifold which includes a first by-pass line controlled by an air-actuated first normally closed valve and a second by-pass line controlled by an air-actuated second normally open valve and by a needle valve, an air motor assembly mechanically connected to the needle valve having a first exhaust outlet and a second exhaust outlet and arranged to rotate the valve element of said needle valve in a clockwise direction when the first exhaust outlet is connected to the atmosphere and in a counterclockwise direction when the second exhaust outlet is connected to the atmosphere, an exhaust valve consisting of a body having four ports and a valve element movable in the valve body arranged to assume a first position connecting the first port to the atmosphere, a second position connecting the second port to the atmosphere, a third position connecting the third port to the atmosphere, a fourth position connecting the fourth port to the atmosphere and a fifth position in which flow of air through all of said ports is prevented, an air line connecting said second port of the exhaust valve to said first exhaust outlet of the air motor assembly, an air line connecting said third port of the exhaust valve to said second exhaust outlet of the air motor assembly, an air line connecting the actu-

ating assembly of said second normally open valve to the first port of said exhaust valve, an air line connecting the actuating assembly of said first normally closed valve to said fourth port of said exhaust valve, and electrical control means actuated by the weight indicator arranged to move the valve element to a selected one of said five positions in response to signals received from said weight indicator.

2. A control system for controlling the speed of rotation of the drawworks of a rotary drilling rig having a weight indicator capable of producing signals varying in response to the changes in the weight carried by the drill bit and having a hydraulic system for altering the weight carried by the drill bit comprising, in combination, a pump mechanically connected to the drawworks for pumping hydraulic fluid upon rotation of the drawworks, a hydraulic circuit connecting an outlet of said pump with an inlet thereof, said hydraulic circuit having a manifold which includes a first by-pass line controlled by an air-actuated first normally closed valve and a second by-pass line controlled by an air-actuated second normally open valve and by a needle valve, an air motor assembly mechanically connected to the needle valve having a first exhaust outlet and a second exhaust outlet and arranged to rotate the valve element of said needle valve in a clockwise direction when the first exhaust outlet is connected to the atmosphere and in a counterclockwise direction when the second exhaust outlet is connected to the atmosphere, an exhaust valve consisting of a valve body having four serially arranged ports, and a valve element movable in the valve body arranged to assume a first position connecting the first port to the atmosphere, a second position connecting a second port to the atmosphere,

a third position connecting the third port to the atmosphere, a fourth position connecting the fourth port to the atmosphere and a fifth position between the second and third positions in which the flow of air through all of said ports is prevented, an air line connecting said second port of the exhaust valve to the first exhaust outlet of the air motor assembly, an air line connecting said third port of the exhaust valve to the second exhaust outlet of the air motor assembly, an air line connecting the actuating assembly of said second normally open valve to the first port of said exhaust valve, an air line connecting the actuating assembly of said first normally closed valve to said fourth port of said exhaust valve, and electrical control means actuated by the weight indicator arranged to move the valve element to a selected one of said five positions in response to signals received from said weight indicator.

3. A device in accordance with claim 2 in which said weight indicator has a rotating pointer shaft and in which the electrically controlled means for moving the valve arrangement includes a rheostat with its slide mechanically connected to the shaft of said weight indicator, and electrically connected with a two-phase motor mechanically linked to the valve element of said exhaust valve.

ROBERT R. CROOKSTON.
